Patented Feb. 10, 1920.

Inventor
Arthur Jutila
By his Attorney

William Richards

UNITED STATES PATENT OFFICE.

ARTHUR JUTILA, OF PLAINFIELD, NEW JERSEY.

PEN-TRAY.

1,330,470.

Specification of Letters Patent.

Patented Feb. 10, 1920.

Application filed February 21, 1919. Serial No. 278,487.

To all whom it may concern:

Be it known that I, ARTHUR JUTILA, a citizen of Finland, residing at Plainfield, county of Union, and State of New Jersey, have invented certain new and useful Improvements in Pen-Trays, of which the following is a specification.

This invention relates to a pen tray and it has for an object to provide a simple and inexpensive device of this kind which may be removably mounted upon an ink bottle and readily attached and detached.

For further comprehension of the invention, and of the objects and advantages thereof, reference will be had to the following description and accompanying drawings, and to the appended claim in which the various novel features of the invention are more particularly set forth.

20 Figure 1. of the drawing is a perspective view of a pen tray embodying the invention showing it in position on an ink bottle.

Fig. 2. is a plan view of the tray.

Fig. 3. is a transverse section on the line 25 3—3 of Fig. 2.

As shown in the drawings my improved pen tray comprises an elongated trough-like member 20 which constitutes the tray proper.

Projecting from one side of this member 20

is an integral neck portion 21 which is bent 30 as shown in Fig. 3 to tightly clasp a resilient strip 23 midway between the ends of the latter. The two halves of this strip are curved, as clearly shown in Fig. 3, so as to clip upon, and partially encircle, the neck 35 6 of the ink bottle 7 as shown in Fig. 1, thus supporting the tray upon the bottle.

The neck 21 terminates in a pair of spring clips 24 which are curved to arciform shape and project outwardly under the tray. As 40 will be apparent the pen may be inserted between the clips 24 and the bottom of the tray 20 when desired, as for instance when the writing materials are being carried from one place to another.

Having thus described my invention and set forth the manner of its construction and use, what I claim as new and desire to secure by Letters Patent is:—

45 A pen tray comprising a tray proper, a pair of spring clips for securing the same to a bottle, and means for securing a pen to said tray comprising a spring bent substantially in the form of an arc and extending under said tray.

55 In testimony whereof I have affixed my signature.

ARTHUR JUTILA.
